UNITED STATES PATENT OFFICE.

PAUL WINTERLICH, OF DAYTON, OHIO.

DESIGN FOR A MIRROR.

Application filed February 28, 1925. Serial No. 12,522. Term of patent 3½ years.

To all whom it may concern:

Be it known that I, PAUL WINTERLICH, a citizen of the United States, residing at Dayton, in the county of Montgomery and State of Ohio, have invented a new, original, and ornamental Design for a Mirror, of which the following is a specification, reference being had to the accompanying drawing, forming part hereof.

The figure of the drawing is a front view of a mirror, showing my new design.

I claim:

The ornamental design for a mirror, as shown.

PAUL WINTERLICH.

Witness:

HOWARD S. SMITH.
